UNITED STATES PATENT OFFICE.

CHARLES D. LANNING, OF DORCHESTER, MASSACHUSETTS.

APPARATUS FOR RECEIVING ELECTRICAL ENERGY.

1,180,510.

Specification of Letters Patent. Patented Apr. 25, 1916.

Application filed December 26, 1905, Serial No. 293,215. Renewed September 9, 1915. Serial No. 49,823.

To all whom it may concern:

Be it known that I, CHARLES D. LANNING, a citizen of the United States, residing at Dorchester, in the county of Suffolk and State of Massachusetts, have invented an Improvement in Apparatus for Receiving Electrical Energy, of which the following description, in connection with the accompanying drawings, is a specification, like letters on the drawings representing like parts.

My invention relates to apparatus for receiving electrical energy, being particularly concerned with the reproduction, retransmission, record or indication of electrical energy, and more especially electrical energy transmitted from a distant point.

My invention will be best understood by reference to the following description when taken in connection with the accompanying illustration of one specific embodiment thereof, while its scope will be more particularly pointed out in the appended claims.

In the drawings.—Figure 1 shows in plan an instrument embodying one form of my invention; Fig. 2 is a sectional elevation on the line 2—2, in Fig. 1; Fig. 3 is a detail in section, partially broken away, taken on the line 3—3 in Fig. 2, and Fig. 4 is a detailed illustration of the separated or interrupted paramagnetic conductor employed in the instrument illustrated.

Referring to the drawings and to the illustrated instrument which embodies one form of the apparatus constituting this invention, the same is shown associated with a conventionally represented telephone circuit and constructed and arranged for use as a telephone repeater. Although this application of my invention is here made for illustrative purposes, it is to be understood that the invention is not limited thereto, but that it may be applied to the receipt of electrical energy in other forms than telephone currents, for the reproduction, utilization, transmission, detection or indication thereof.

In its details, as shown for illustration, the repeating instrument is provided with a receiving coil *a* of any suitable construction, but preferably, when applied to the purposes described, wound for inclusion, directly or indirectly, in a telephone receiving circuit *b*, the latter conventionally shown in Fig. 1 as leading to a distant station A, where it is provided with the usual and ordinary transmitter *c*, battery *d* and induction coil *e*. The telephone circuit *b* is shown as connect-

ed directly to binding posts *f*, *f* upon the baseboard *g* of the instrument, connection being thence had to the binding posts *h*, *h*, as indicated by dotted lines, and thence to the receiving coil by the terminal plugs *i*, *i* and flexible leads *j*, *j*.

The application of this invention being illustrative only and not being concerned particularly with the circuiting of the telephone lines, the same is here shown arranged as a one-way repeater only for repeating voice currents generated at the sending station A to the receiving station B, the latter having the usual telephone receiver *k*. The receiving station B is connected to the instrument at the supposed repeating station by the line circuit *l*, the latter being inductively related to the local or repeating circuit *m* through the induction coil *n*. The local circuit is connected to binding posts *o* and then passes by underneath connections to the supporting posts *p*, there being preferably provided some source of electro-motive force, such as the battery *q*, for maintaining a preferably constant current flow in the local circuit. The supporting posts are vertically split part way down to receive and support the projecting ends of the receiving magnet core *r*, which herein consists of a soft iron rod of suitable dimensions. The clamping screws *s*, *s* threaded into the split ends of the posts clamp the ends of the core firmly in position and afford good conductive contact between the posts and the core, the local circuit being therefore completed through the paramagnetic conducting core of the receiving magnet. The magnetic circuit of the receiving magnet is completed by means of the U-shaped bar *M*, which is preferably of hardened steel and permanently magnetized. The magnet bar is concaved slightly at its end face to fit the curvature of the core rod sides. The latter are separated from the bar by a thin sheet of insulating material *t*, but are pressed toward the bar ends by pressure screws *u* to reduce to a minimum the effect of the break in increasing the magnetic reluctance of the circuit.

It will be observed that in its normal condition the apparatus described has a current, and herein a substantially constant current, continuously flowing through the local circuit and therefore lengthwise through the core of the receiving magnet,

I have found that by suitably relating the initial flux which is thus set up to the variable flux created by the line current energy, which relation in the instrument shown may 5 be provided for by suitably forming or proportioning the magnetic circuit traversed by the magnetic flux of the receiving magnet, the current undulations of the receiving circuit may be accurately reproduced, without 10 distortion and with intensification, in the local circuit and impressed upon the current flowing therein for transmission to the distant station B through the medium of the induction coil n . This action I believe 15 is to be due to the choking effect of the receiving magnet flux passing lengthwise the magnet core upon the magnetic flux generated by the local current, and in the described 20 form of apparatus maintained circumferentially and exterior to the core or that part of the core forming the conducting path for the local current. One formation of the core which I have found effective for reproduction 25 of energy variation in the receiving circuit is shown in the drawings, where the core is separated into sub-divisions v , which abut against each other to give good electrical contact but present opposed convex end faces, so that the continuity of the core is 30 interrupted, or partially interrupted, at those places by an air gap which converges toward the axial contact points or areas of the adjacent faces. To press the separated core portions into firm contact there is provided 35 at one end of the instrument the horizontal end pressure screw w , threaded into the side of the upright support x to aline with the magnet core and adapted, after the clamping screws s have been turned, to 40 clamp the farther end of the core rod and loosen the nearer end thereof to force the core portions into firm contact with each other, the set screw y being then screwed down to maintain them in that condition. 45 An adjusting screw z is located beneath the magnet to properly support the latter for suitable alinement with its core rods.

The action of this instrument I account for on the following grounds: The magnetic 50 flux normally generated by the constantly flowing local current, which flux is circumferential and exterior to the conducting core members, is naturally concentrated or intensified in the air gap separations of the core, 55 reaching its greatest intensification immediately adjacent the area of contact between adjacent faces, the contact in the illustrated form being supposed to be little more than mere point contact. When the current 60 impulse is received by the magnet coil, the core sections, being in metallic contact to but a slight extent, and the continuous metallic circuit afforded by the metallically contacting portions of the core being partially or 65 wholly saturated by the initial, and herein

permanent magnetism, of the bar M passing longitudinally through the core, the added flux, due to the energy impulse in the receiving magnet, is forced or spread out at these contracted core points exterior to the 70 conductor core and into the adjacent converging air gap, this added longitudinal flux, however, where it passes through the air gap being naturally most highly concentrated adjacent the point or area of contact 75 where the air gap provides a path of low magnetic reluctance. This concentration of the longitudinal flux into the region necessarily occupied by the intensified circumferential flux causes the former to choke down 80 the latter and, by reducing the flux inclosing the conductor, produces a momentary reduction in the local current, thus reproducing, as an intensified energy impulse or variation in the local circuit, the energy impulse or variation in the receiving circuit. In the instrument shown this effect is wholly 85 magnetic, for it will be evident that no purely inductive action can be maintained between the two cross fluxes and no microphonic action due to variable contact between the separated core portions, as has 90 been and can be readily demonstrated by experiment.

In the illustrated instrument I have described a form of apparatus well adapted to carry out my invention and arranged to suitably relate the initial flux of the local circuit to the controlling flux of the receiving circuit, but it is to be understood that extensive departures from the disclosed form 95 of apparatus and the described method may be made without departing from the spirit of my invention. The apparatus disclosed is efficient for the purposes described, but it is obvious that the initial flux may be generated by means other than the constantly 100 flowing current and that the desired action of the controlling flux upon the initial flux may take place without the necessary passage of the controlling flux through the body of the local conductor, or without the passage of the local circuit through the core of the receiving magnet coil, or in the instrument shown without the particular proportioning and formation of the core disclosed, or without other conditions which are here 105 described for the purpose of fully illustrating one operative embodiment of this invention.

It is to be noticed that the provision of a number of contracted air gap-producing core portions secures a considerable and effective cumulative magnetic action, increasing considerably the efficiency of the instrument. At the same time the formation of the core portion and the arrangement of the magnetic elements are such, and the air gap which the longitudinal flux is compelled to 115 traverse is so slight, that the magnetic reluc- 120

tance of the circuit is extremely low and the effectiveness of the receiving magnet raised to a maximum.

Claims:

5. 1. A current receiving device having a receiving magnet, a core therefor having a plurality of reduced portions of magnetic material in magnetic contact with each other, and a local circuit including the magnet core.
10. 2. A current receiving apparatus having a receiving magnet having a core provided with sub-divided portions having convex contacting ends of magnetic metal and a local circuit including the magnet core.
15. 3. A current receiving apparatus having a receiving magnet having a core provided with sub-divided portions having convex contacting ends of magnetic metal and a local circuit including the magnet core, and a source of constant electro-motive force for said circuit.
20. 4. A current receiving apparatus having a receiving magnet having a core provided with sub-divided portions of magnetic material having convex contacting ends also of magnetic metal and a local circuit including the magnet core, a source of constant electro-motive force for said circuit, and means for initially magnetizing said core.
25. 5. A current receiving apparatus having a local circuit, a receiving magnet and a core for the receiving magnet having separate metallic magnetic portions with diverging metallic walls in contact with each other, said core also serving as a part of the said local circuit.
30. 6. A current receiving apparatus having a local circuit composed in part of two iron bodies in contact with each other, but having their walls diverging from the region of contact, and a receiving magnet in inductive relation to said bodies.
35. 7. A receiving apparatus having a receiving coil, a core for said coil having a pair of cylindrical iron core pieces abutting one against the other and having walls diverging from the region of contact, and a local circuit electrically associated with said core.
40. 8. A receiving apparatus having a receiving coil, an initially magnetized core for said coil having a pair of cylindrical iron core pieces abutting one against the other and having walls diverging from the region of contact, and a local circuit associated with said core.
45. 9. A receiving device having a receiving coil, a core of magnetic material therefor, said core being of substantially unchanging resistance under the magnetic influence of the receiving coil and providing a continuous magnetic conductor, said material being removed at one or more points lengthwise
50. the core to provide one or more points of increased magnetic reluctance, and a local circuit connected with the said core.
55. 10. A receiving apparatus having a receiving coil, a core for said coil having a pair of iron core pieces abutting each with its iron walls against the iron walls of the other and having walls diverging from the region of contact, and a local circuit electrically associated with said core.
60. 11. A current-receiving device having a receiving magnet provided with a core, said core being of substantially unchanging resistance under the magnetic influence of the magnet, and said core consisting of sub-divided portions having abutting ends with diverging walls, and a local circuit including the magnetic core.
65. 12. A current-receiving apparatus having a receiving magnet, a core therefor of substantially unchanging resistance under the magnetic influence of the magnet, a local circuit non-inductively related to the magnet and including the said core, and means magnetically to reproduce energy variations in said local circuit through variations in the receiving magnet.
70. 13. A current-receiving apparatus having a receiving magnet, a local circuit non-inductively related thereto, and means for non-inductively choking the magnetic flux generated by the current in said local circuit through variations in the strength of the receiving magnet.
75. 14. In an instrument for controlling the flow of electrical current in a conductor the combination with a conductor composed of magnetic metal and having a portion of reduced minimum cross section with its walls thereat converging toward the conductor axis of means for generating a longitudinal flux through said conductor independent of the current-caused circumferential flux of the conductor.
80. 15. In an instrument for controlling the flow of electrical current in a conductor, the combination with a conductor composed of a plurality of sections of magnetic metal presenting contacting walls converging toward the conductor axis, of means comprising a solenoid surrounding the said conductor for generating a longitudinal flux through the same independent of the current-caused circumferential flux of the conductor.
85. In testimony whereof, I have signed my name to this specification in the presence of two subscribing witnesses.

CHARLES D. LANNING.
